(57) **CLAIM**

The ornamental design for a baby camera, substantially as shown and described.

DESCRIPTION

FIG. 1 is a top, front and right side perspective view of a baby camera showing my new design;

FIG. 2 is a bottom, back and left side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines shown in the drawings are included for the purpose of illustrating portions of the baby camera, and form no part of the claim design.
